(57) **CLAIM**

The ornamental design for a portion of a buckle, as shown and described.

DESCRIPTION

1. Portion of a Buckle

1.1 : Perspective

1.2 : Front

1.3 : Back

1.4 : Right

1.5 : Top

1.6 : Bottom

1.7 : End view cut at middle portion

The broken lines are for the purpose of illustrating the unclaimed portion of a buckle which form no part of the claimed designs; the dot and dashed lines shown in design 1 are boundaries between the claimed portion and the non-claimed portion; the parallel thin lines (shading lines) shown on the surface of the buckles are used to specify a three dimensional shape of the claimed portion of a buckle.
